UNITED STATES PATENT OFFICE.

ANTHONY T. STOCK, OF DAYTON, OHIO, ASSIGNOR TO DELCO-LIGHT COMPANY, OF DAYTON, OHIO, A CORPORATION OF DELAWARE.

REFRIGERATING APPARATUS.

Application filed July 26, 1926. Serial No. 124,860.

The present invention relates to refrigerating apparatus, and particularly to apparatus in which the refrigerant condenser is cooled by water.

5 One of the objects of the present invention is to reduce the cost of operating a refrigerating apparatus by controlling the flow of water for condensing purposes in a manner such that the water begins to flow 10 when the demand for water arises and stops flowing promptly after the demand ceases.

Further objects of the present invention will be apparent from the following description, reference being had to the accompanying 15 drawings, wherein a preferred form of the present invention is clearly shown.

In the drawings:

Fig. 1 is a diagrammatic view of a refrigerating apparatus including a water-cooled 20 condenser and showing the present improvements applied thereto;

Fig. 2 is an end view of a valve utilized in the apparatus, the view being taken looking in the direction of arrow 2 in Fig. 1; 25 and

Fig. 3 is a sectional view taken on line 3—3 of Fig. 2.

Referring to the drawings, for the purpose of illustrating the present invention 30 there is disclosed a compression, condensing and expansion type refrigerating apparatus which includes, chiefly, a cooling unit or evaporator 20, a compressor 21, a driving motor 22 for said compressor and a condenser 23. A fitting 25 is connected with the high-pressure side of the compressor 21 and by a pipe 26 with condenser coil 27. Condenser coil 27 is connected by a pipe 28 which is connected with the header of the 35 evaporator 20, which header may contain a float valve (not shown) or any suitable pressure-reducing valve. Refrigerant is withdrawn from the evaporator 20 by the compressor 21 through a pipe 29. The condenser coil 27 is enclosed within a tank 30, adapted to be supplied with water through a pipe 31 and drained through a pipe 32. Pipe 31 and a water inlet pipe 33 are connected with the fitting 25 which contains a 40 valve adapted to control the flow of water to the condenser tank 30.

Fitting 25 comprises a casting or body 35 including a nipple 36 by which said body is secured to the outlet of the compressor 21. 45 The opening 37 of the nipple 36 communi-

cates with a chamber 38, and a nipple 39 provided on the opposite side of the casting is secured to the pipe 26. Thus refrigerant passing from the compressor to the condenser coil 27 will pass through the chamber 38. A cage 40 is secured by screws 41 to the body 35, and contains a metallic bellows 42 secured to body 35 at 43 and having a non-collapsible extension 44 located within the chamber 38. The bellows 42 is adapted to contain a volatile fluid which is introduced through a tube 45 which extends through the body 35. Pipe 45 is sealed at 45^a after the bellows 42 has been charged with volatile fluid. The upper end of the bellows 42 carries a stem 47 which is screw-threaded and adapted to be received by a nut 48. The end of the cage 40 is threaded and cooperates with an adjusting nut 49. A spring 50 surrounds the stem 47 and is interposed between the nut 49 and the top wall of the bellows 42. The nut 49 is adapted to be screwed inwardly or outwardly for regulating the resistance of the spring 50 to movement of the bellows 42.

The fitting 25 includes a body 52 which is attached to the body 35 and includes a chamber 53 connected with the pipe 33 containing a ball valve 54. A spring 55 tends normally to maintain the valve 54 upon its seat 56. Chamber 53 is connected by a passage 57 with a chamber 58 which is provided with a flexible wall 59. A stem 60 extends through the flexible wall 59 and passage 57, and is adapted to engage the ball valve 54. Stem 60 is adapted to be moved inwardly by a lever 61 which is fulcrumed on a pin 62 carried by ears 63 formed upon the body 52. The opposite end of lever 61 lies in the path of movement of the nut 48, whereby the outward movement of the nut 48 and stem 47, caused by the expansion of the bellows 42, will rotate the lever 61, and move valve 54 from its seat 56. Body 52 is provided with a passage 65 which communicates with a passage 66 formed within the body 35. Passage 65 is connected with pipe 31. When the valve 54 is open, water will flow from pipe 33 through chamber 53, passage 57, chamber 58 and passages 65 and 66 and pipe 31 to the condenser 23. Charging tube 45 extends through the passage 66 in chamber 35 and is, therefore, subjected to the temperature of the water passing to the condenser 23.

The compressor 21 may be started and stopped automatically by any suitable controller so that a desired average temperature will be maintained in a cabinet which contains the cooling unit 20. For example, the controller may be of the type which is responsive to pressure in the low pressure line, such as described and claimed in the copending application of Jesse G. King, Serial No. 642,368, filed May 30, 1923. This controller is illustrated diagrammatically at 70, and includes a snap switch having contacts 71 and 72 for controlling the circuit of the motor 22, and a metal bellows 73 having a movable end wall mechanically connected with the switch. The bellows 73 is connected by a pipe 74 with the low pressure pipe 29. When the pressure in pipe 29 exceeds a certain value, corresponding to high temperature in the unit 20, the switch contacts 71 and 72 will be closed to cause the motor 22 to drive the compressor 21. When the pressure in pipe 29 falls below a certain low pressure, corresponding to a low temperature in the unit 20, the switch contacts will be separated to stop the motor and compressor.

When the compressor is operating, the relatively warm refrigerant which passes through the chamber 38 will quickly heat the extension 44 of bellows 42, causing the fluid within the bellows 42 to expand, whereby the stem 47 and nut 48 are moved outwardly to open the valve 54. Water will then flow through pipe 33, valve 25 and pipe 31 to the condenser chamber 30. When the compressor is stopped, relatively warm refrigerant ceases to flow through chamber 38, and the relatively cold water passing through the body 35 to the condenser chamber 30 will quickly cool the charging tube 45, whereby the bellows will quickly contract and the ball valve will then be forced against its seat 56 by the spring 55, to stop the flow of water.

It is apparent from the foregoing description that a refrigerating apparatus has been provided which utilizes water for the condenser in an economical manner, because the water is shut off promptly after the demand therefor ceases. By subjecting the temperature responsive mechanism controlling the water valve 54 to the cooling action of the water flowing to the condenser, the valve will be closed promptly after flow of refrigerant ceases.

The temperature at which the valve 54 opens can be controlled by turning the nut 49. When the nut 49 is screwed inwardly,

the stem 47 also will be moved inwardly because the spring 50 is additionally compressed. In order to maintain the desired clearance between nut 48 and lever 61, the nut 48 is screwed outwardly. Conversely, when the nut 49 is screwed outwardly to reduce the compression of spring 50, the stem 47 will move outwardly; and the nut 48 may be screwed inwardly to maintain the clearance between it and the lever 61.

While the form of embodiment of the present invention as herein disclosed, constitutes a preferred form, it is to be understood that other forms might be adopted, all coming within the scope of the claims which follow.

What is claimed is as follows:

1. A refrigerating apparatus comprising a refrigerant circulatory system having means for circulating the refrigerant in said system and having a condenser portion; a cooling medium circuit for said condenser portion; and means responsive to the temperature of the refrigerant and the medium in said circuit for controlling the flow of said medium.

2. A refrigerating apparatus comprising a refrigerant circulatory system having means for circulating the refrigerant in said system and having a condenser portion; a cooling medium circuit for said condenser portion; and means for controlling the flow of medium in said circuit, said means including an expansible vessel containing a volatile fluid subjected to the temperature of the refrigerant in the system and the temperature of cooling medium, and a valve operatively connected with said vessel.

3. A refrigerating apparatus including an evaporator, a condenser, a compressor, conduits operatively connecting same; a cooling medium circuit for said condenser; and a valve responsive to the refrigerant temperature between the compressor and condenser and responsive to the temperature of the cooling medium.

4. A refrigerating apparatus including an evaporator, a condenser, a compressor, conduits operatively connecting same; a cooling medium circuit for said condenser; and a valve responsive to the refrigerant temperature between the compressor and condenser and responsive to the temperature of the cooling medium before said medium is delivered to the condenser.

In testimony whereof I hereto affix my signature.

ANTHONY T. STOCK.
